UNITED STATES PATENT OFFICE.

CHARLES A. STICKNEY, OF CHATTANOOGA, TENNESSEE, ASSIGNOR, BY DIRECT AND MESNE ASSIGNMENTS, TO ADDRESSOGRAPH COMPANY, OF CHICAGO, ILLINOIS, A CORPORATION OF ILLINOIS.

EMBOSSING-DIE.

1,299,518.

Specification of Letters Patent.

Patented Apr. 8, 1919.

Application filed April 8, 1918. Serial No. 227,268.

To all whom it may concern:

Be it known that I, CHARLES A. STICKNEY, a citizen of the United States, and resident of Chattanooga, Tennessee, have invented 5 certain new and useful Improvements in Embossing-Dies, of which the following is a specification.

My invention relates to dies for embossing printing plates used in addressing machines, 10 and the invention consists in the features hereinafter described and particularly pointed out in the claims.

In the accompanying drawings Figure 1 is a sectional view of a pair of dies taken in 15 the direction longitudinally of the line of embossings to be made in the plate, representing the first embossing action in the printing plate.

Fig. 2 is a view similar to Fig. 1, showing 20 the second action or embossing about to be performed upon the printing plate.

Fig. 3, is a plan view of the female die and showing in dotted lines the relative position of the previous embossing, and representing in dotted lines also the relation of 25 the die to the previous embossing it being understood, however, that the die action takes place at the same location and that the printing plate is moved step by step to have 30 the successive embossings made therein.

Fig. 4, is a perspective view of the female die.

Fig. 5, is a perspective view of the punch.

As shown in Fig. 4 the die face 1 has 35 formed therein the groove or depression into which the metal of the plate is forced to form the embossed character.

In the present instance the character is the letter *l* but this of course is representative 40 of any and all characters necessary to make up the alphabet or numerical system. At four points around the face of the die projections 45 2 are located. These projections are at the sides of the die face 1, and lie between the extended planes of the upper and lower edges 1' 1'' of the said die face, so that it will be observed the two projections at the top of the die face are separated by a space equal substantially to the width of the die face and this is true also of the projections 50 at the lower edge of the die.

Considering the two projections lying at the side edge of the die face *i. e.* the one at the top and the other at the bottom of the 55 die on the same side thereof it will be seen

that these are separated by recesses 3 of considerable depth, these recesses lying beyond the side edges of the field or plane face of the die in which the character forming recess is located.

This female die illustrated in Fig. 4 cooperates with a punch 4 having the character forming rib or projection 4' conforming of course to the depression in the face 1 of the die. This rib or projection 4' is on the 65 lower face of the raised portion 4^a of the punch which is of an area slightly less than the area of the plane face of the die 1 except those areas lying between the two upper projections and the two lower projections.

In action upon the metal of the plate being embossed it will be understood that the metal is free to be drawn through the spaces 70 *a*, *b*, at top and bottom of the die between the upper pair of points 2 and between the lower pair of points 2 respectively, and this is in addition to the freedom which is permitted to the metal to be drawn between the points at the sides of the die.

The points 2 support the metal about the character being embossed in the plane of the body of the plate and prevent tipping of the base upon which the character is formed thus avoiding the necessity of truing up the 85 line of characters after being formed.

Figs. 1 and 2 represent the action of the dies upon the plate. Fig. 1 illustrating the first embossing effect, and Fig. 2 the next embossing action about to take place, from 90 which it will be seen that during the second embossing action the character which is already embossed will overlie, substantially the recess 3 at the side of the die and there will be no blanking out action of the dies on 95 this embossed character. This is illustrated also in Fig. 3.

The shift of the plates being embossed relative to the dies is less than the width of the dies, and at each die action the metal of 100 the plate where the widely separated points 2 contact therewith is maintained in the same plane with the body of the plate while the metal is free to be drawn through the spaces between the points.

Another effect which I secure by my improved die is that close line spacing can be obtained, for it will be observed from Fig. 4 that the groove for forming the characters may extend to a point nearly if not quite be- 110

tween the lower pair of projections and this may be the case also with the top of the letter in respect to the space between the upper pair of projections.

5. The four points support the metal of the plate as far removed from the character as possible.

I claim—

1. A die for embossing characters in addressing plates having a die face with a character forming groove therein, and with a projection adjacent each of the four corners of said face extending above the same and with recesses below the plane of the die face between the pairs of projections at the sides of said face, substantially as described.
10. A die for embossing characters in addressing plates having a die face with a character forming groove therein, and with a projection adjacent each of the four corners of said face extending above the same and with recesses below the plane of the die face between the pairs of projections at the sides of said face, substantially as described.
15. A die for embossing characters in addressing plates having a die face with a character forming groove therein, and with a projection adjacent each of the four corners of said face extending above the same and with recesses below the plane of the die face between the pairs of projections at the sides of said face, the face of the die 20 extending in between the upper and lower pairs of projections and terminating substantially in line with the outer faces of said projections, substantially as described.
- 25.

Copies of this patent may be obtained for five cents each, by addressing the "Commissioner of Patents Washington, D. C."

3. A die having a face with a character forming groove therein and with a projection adjacent each of the four corners of the said face which extends in between the projections of the upper and lower parts of the die, the groove for forming the character extending substantially to a point in line with the inner side of the adjacent pair of projections, substantially as described.

4. In combination, a die having a face with a character forming groove therein, and with four projections extending above said face, one adjacent each corner thereof, said face having extensions in its own plane between the projections of the upper and lower pairs, and a punch having a character forming rib on a raised portion the face of which is of an area less than that defined by the inner corners of the projections, substantially as described.

5. A die having a face with a character forming groove therein, a pair of projections extending above said face, the latter extending in between said projections, substantially as described.

In testimony whereof, I affix my signature.

CHARLES A. STICKNEY.
